CLAIM

The ornamental design for a pet hair remover roller as shown and described.

DESCRIPTION

FIG. 1 is a top, front and right side perspective view of a pet hair remover roller showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and right side perspective view of the pet hair remover roller showing the front portion of the roller housing in an open position and the handle in a stored state;

FIG. 10 is an enlarged view of portion 10 in FIG. 2; and,

FIG. 11 is an enlarged view of portion 11 in FIG. 2.

The evenly-spaced broken lines shown in the drawings illustrate portions of the pet hair remover roller that form no part of the claimed design. The short-dash, long-dash lines depict the bounds of the enlarged portions that form no part of the claimed design.

1 Claim, 11 Drawing Sheets
